LAVATORY BASIN

John Fortuno, 2537 Seaman Ave.,
South El Monte, Calif. 91733

Filed Sept. 20, 1968, Ser. No. 13,625

Term of patent 14 years

Int. Cl. D23—02

U.S. Cl. D23—58

FIG. 1.

FIG. 2.

FIG. 4.

FIG. 3.

FIGURE 1 is a perspective view of a lavatory basin showing my design;

FIGURE 2 is a front elevational view thereof;

FIGURE 3 is a right side elevational view thereof; and

FIGURE 4 is a fragmentary perspective view, showing in enlarged detail, one of the two soap dish recesses formed in the upper surface of the lavatory basin.

I claim:

The ornamental design for a lavatory basin, as shown.
